UNITED STATES PATENT OFFICE.

CHARLES EDOUARD PIERRE GOURDOU, OF LE-PARC-ST.-MAUR, FRANCE.

MOTION-AMPLIFYING DEVICE.

Application filed May 5, 1924, Serial No. 711,215, and in France May 16, 1923.

The object of this invention is to provide an improved motion-amplifying device which is applicable generally to any and all apparatus in which the displacement of a movable part or member is to be measured, but which is specially applicable to registering barometers.

The device according to my invention consists essentially of a flexible blade or wire suitably wound around and tensioned on pins or studs carried by a movable attachment, one end of which blade is secured to the part whose displacement is to be measured, while its other end is secured to a stationary frame. The movable attachment carries a pointer that indicates or registers the displacements of the movable end of the blade, and said attachment is subjected to the action of an adjustable spring which opposes or resists the movement thereof and which is fastened at opposite ends to the attachment and to the stationary frame.

In the accompanying drawings:

Figure 1 is a diagrammatic side elevation of the complete invention;

Fig. 2 is an enlarged detail view, illustrating the winding of the flexible blade or wire around the pins carried by the movable attachment;

Fig. 3 is a detail view of the aforesaid attachment; and

Fig. 4 is a view showing a possible method of adjusting the resistance spring of the device.

Referring to Fig. 1, *a* indicates a set of aneroid vessels connected together in superposed relation, the under wall of the lower vessel being secured to a frame *b*. The top wall of the upper vessel serves as an attaching point for one end of a flexible blade *c* (for instance, a steel band of .04 millimeter thickness), which is wound around a series of pins *d*, *e*, *f*, *g* carried by and securely set into a small movable attachment or slide *h*; the other end of the blade being fastened to a stationary frame *b'*.

The attachment or slide *h*, as shown in Fig. 3, consists of a U-shaped strip of sheet metal, the two opposite faces of the U being provided with holes to receive the pin ends.

In the mean or normal position of this member, the pins *d* and *g* will be disposed in a horizontal line (as will be apparent from Fig. 2), while pins *e* and *f* will be disposed in an oblique line which is so positioned as to permit the blade to pass freely between

the first-named pins. Due to this arrangement, the attachment will be held on blade *c* without any sliding movement thereof along the blade being possible as soon as 60 the tension exerted on the blade is sufficient, the arcs of winding being of considerable extent. In case a wire is used, instead of a band, to form the blade, the wire can be wound several times around the two pins 65 *f* and *e*, these pins serving merely as an attaching means.

A spring *i* (Figs. 1 and 4) is secured at opposite ends to slide *h* and frame *b'*, and tends to oppose the movement of the former, its attachment to the slide being effected by means of a loop or eye in the usual way, or in some other preferred manner. The said slide has secured to it the pointer or indicator *m* which is designed 75 to register on a suitable scale (not shown) the displacements of the movable end of the blade; the amplification ratio, in mean position of the parts, being equal to the ratio 80 between the length of the pointer and the inside distance between pins *d* and *g*. The scale referred to may take the form of a drum whereon the pointer records its movements, or it may consist of a graduated dial, 85 in front of which the pointer moves, the precise character of the scale being immaterial to the invention itself.

To reduce friction between the side and its resistance spring *i* as far as possible, the bottom of the former may be suitably rounded, as indicated at *k* in Fig. 3, and the lower end *i'* of the spring may be flattened into a very thin blade (Fig. 4) which is wound around the said rounded portion *k*. The length of the spring may be adjusted by means of a small U-shaped metal member *v* having a hole in one arm thereof through which one end of the spring is inserted; the other arm of said member being introduced between two spires of the spring. By turning this member *v* more or less around the spring, a greater or lesser number of spires of the spring can be brought into operation. Tensioning of the spring can be effected by means of a nut *l* (Fig. 4) on its threaded, non-flattened end, 105 said nut bearing against a washer *l'* supported on the stationary frame *b'*.

The above-described device is applicable 110 to all measuring apparatus, where the displacement of a movable part of member (in the present instance, the top wall of the

upper aneroid vessel *a*) is to be measured. Obviously both ends of blade *c* might be movable, and in that event the pointer would have a total displacement which is twice as great, since in such case each end of the blade would move the same distance as the movable end of the blade when the other end of the latter is fixed. In either case, moreover, lost motion in all the transmission parts is avoided.

I claim as my invention:—

1. Apparatus for measuring the extent of movement of a moving part, comprising a flexible element connected at one end to the part whose movement is to be measured, so as to be directly and positively stressed by such movement; a support to which the other end of said element is connected; a member movably mounted on the flexible element intermediate the ends thereof and provided with an indicator, said member adapted to turn relatively to said element consequent upon the stressing of the latter; and a spring connected to said member to oppose such turning movement.

2. Apparatus for measuring the extent of movement of a moving part, comprising a flexible element connected at one end to the part whose movement is to be measured, so as to be directly and positively stressed by such movement; a support to which the other end of said element is connected; a member movable mounted on the flexible element and provided with a set of pins around which said element is wound intermediate its ends, and also provided with an indicator, said member adapted to be turned relatively to said element by the action of the latter on said pins consequent upon its being stressed; and a spring connected to said member to oppose such turning movement.

3. Apparatus for measuring the extent of movement of a moving part, comprising a flexible element connected at one end to the moving part; a support to which the other end of said element is connected; a U-shaped attachment movably mounted on the flexible element and having a set of pins disposed transversely between its sides, around

which pins said element is wound intermediate its ends, said attachment adapted to turn relatively to said element during the movement of said moving part; a spring connected to said element to oppose such turning movement; and a pointer carried by said attachment.

4. Measuring apparatus, according to claim 3, in which two of the pins are mounted in spaced, horizontal relation, the other two being disposed in an oblique line which passes through the space between the first two.

5. Apparatus for measuring the extent of movement of a moving part, comprising a flexible element connected at one end to the part whose movement is to be measured, so as to be directly and positively stressed by such movement; a support to which the other end of said element is connected; a member movably mounted on the flexible element intermediate the ends thereof and provided with an indicator, said member adapted to rotate relatively to said element consequent upon the stressing of the latter and having a portion thereof which is engaged by said element rounded to prevent slippage between said parts and to permit such rotation without friction; and a spring connected to oppose said rotation.

6. Apparatus for measuring the extent of movement of a moving part, comprising a flexible element connected at one end to the moving part; a support to which the other end of said element is connected; a member movably mounted on the flexible element and provided with a set of pins around which said element is wound intermediate its ends, said member adapted to rotate relatively to said element during the movement of said movable part and having a portion thereof which is engaged by said element rounded to prevent slippage between said parts and to permit such rotation without friction; a pointer carried by said member; and a spring connected to oppose said rotation.

In testimony whereof I have affixed my signature.

CHARLES EDOUARD PIERRE GOURDOU.
